UNITED STATES PATENT OFFICE.

ROBERT REICHLING, OF BERNBURG, PRUSSIA, GERMANY.

ELECTRIC SAFETY ATTACHMENT FOR STEAM-BOILERS.

SPECIFICATION forming part of Letters Patent No. 352,203, dated November 9, 1886.

Application filed March 11, 1886. Serial No. 194,806. (No model.) Patented in Germany February 10, 1885, No. 32,552.

To all whom it may concern:

Be it known that I, ROBERT REICHLING, of Bernburg, Germany, have invented a new and Improved Electric Safety Attachment for 5 Steam-Boilers, (for which a patent has been granted in Germany, No. 32,552, February 10, 1885,) of which the following specification is a full, clear, and exact description.

This invention relates to an electric attachment for steam-boilers, by means of which an alarm is sounded whenever the water within the boiler reaches its minimum safety height.

The invention consists in the elements of improvement hereinafter more fully pointed out.

15 The accompanying drawing represents a longitudinal central section, partly in side view, of my improved safety attachment.

The letter *a* represents a tube, which reaches down to the plane of the lowest water-line desired within the boiler. The upper end of the tube *a* is screwed into the lower end of a valve-case, *b*, having upright ribs *d*, that constitute guides for a cup-shaped valve, *c*. The valve *c* carries a central isolated plate, *r*, and is provided with a ring, *f*, of easily-fusible metal.

25 Upon the ring *f* there is supported a case, *g*, held down by a nut, *h*, that surrounds the upper part of case *b*. In place of ring *f* the space within the ribs *d* may be filled up with a readi-

30 ly-fusible material. The case *g* carries the isolated plate *i*, which is provided with the two pole ends *n* and *p* of an electric battery. The outer rim, *c'*, of the valve *c* is placed beneath an abutment, *b'*, of valve-case *b*, and thus a

space, *d'*, is formed between valve and valve-case.

The water being at a proper level within the boiler, fills or partly fills tube *a*. When the water, however, falls beneath the mouth of the tube, steam is free to enter the same. 40 The steam will melt ring *f* and lift valve *c*, thus establishing contact between plate *r* and pole ends *n p*, to sound an alarm. The space *d'* is at the same time closed.

To introduce a new ring, *f*, the nut *h* and 45 case *g* are removed, the valve *c* is cleaned, and, after the ring has been put in position, the parts are reapplied.

I claim as my invention—

1. The combination of valve-case *b* and valve 50 *c*, having isolated plate *r*, with the fusible ring *f*, and with the case *g*, having poles *n p*, and secured to valve-case *b*, substantially as specified.

2. The combination of valve-case *b* and valve 55 *c*, having plate *r*, with fusible ring *f*, case *g*, poles *n p*, and nut *h*, all being so constructed that a space, *d'*, is formed between the valve-case and the upper end of the valve, substantially as specified.

60 In testimony whereof I have signed my name to this specification in the presence of two subscribing witnesses.

R. REICHLING.
